DESIGN FOR A VEHICLE SIGNAL

Victor E. Jossenberger, Long Beach, Calif., and
Ivan Bankoff, Revere, Mass.

Application March 17, 1939, Serial No. 83,652

Term of patent 14 years

To all whom it may concern:

Be it known that we, Victor E. Jossenberger and Ivan Bankoff, citizens of the United States, residing at Long Beach, in the county of Los Angeles and State of California, and Revere, in the county of Suffolk and State of Massachusetts, respectively, have invented a new, original, and ornamental Design for a Vehicle Signal, of which the following is a specification, reference being had to the accompanying drawing forming a part thereof.

Figure 1 is a front elevation of the vehicle signal, showing our new design.

Figure 2 is a side elevation of the same.

We claim:

The ornamental design for a vehicle signal, as shown.

VICTOR E. JOSSENBERGER.
IVAN BANKOFF.
